CHARLES ALGERNON PARSONS, OF NEWCASTLE-UPON-TYNE, AND STANLEY SMITH COOK, OF WALLSEND, ENGLAND; SAID COOK ASSIGNOR TO SAID PARSONS.

WATER-TUBE BOILER.

1,210,976.

Specification of Letters Patent. Patented Jan. 2, 1917.

Application filed April 10, 1913. Serial No. 760,287.

To all whom it may concern:

Be it known that we, CHARLES ALGERNON PARSONS, K. C. B., of Heaton Works, Newcastle-upon-Tyne, in the county of Northumberland, England, and STANLEY SMITH COOK, of Turbinia Works, Wallsend-on-Tyne, in the county of Northumberland, England, subjects of the King of Great Britain and Ireland, have invented certain new and useful Improvements in and Relating to Water-Tube Boilers, of which the following is a specification.

This invention relates to improvements in water tube boilers and more particularly to super-heating means therefor. Such means usually consist of additional tubes which are exposed to the flames and hot gases of combustion, and through which the steam passes after leaving the steam drum.

The object of the present invention is to avoid the excessive heating of these tubes when for any reason such as a reduction of power or the sudden shutting down of the engines, the flow of steam through them is reduced or stopped altogether, while under normal conditions an efficient superheat is obtained.

The invention consists in a water tube boiler having superheater tubes arranged in single rows intermeshed with some or all of the water heating tubes in close proximity thereto, so that the mutual heat radiation between these superheater and water tubes shall prevent the former from attaining an excessive temperature at such times as the flow of steam therethrough is reduced or stopped.

The invention also consists in the improved arrangements of the water heating means and superheater means in a water tube boiler as hereinafter described.

The invention is shown carried into effect in the accompanying drawing in connection with a water tube boiler of a usual construction having a steam drum, *a*, connected by means of water tubes, *b*, to two lower water drums, *c*, between which the fire grate is arranged. On the left hand side of the figure are shown additional tubes, *d*, connecting the steam drum, *a*, with a chamber, *e*, within the lower drum, *c*, these additional tubes being provided for the purpose of pre-heating the boiler feed water before it is passed into the drums, *c*, and evaporated in the water tubes, *b*.

The necessary degree of superheat is imparted to the steam by passing the same from the steam drum, *a*, through a series of superheating tubes, *f*, arranged in single rows and transversely to the tubes, *b*. The superheating tubes *f*, it will be seen are intermeshed entirely with the tubes, *b*, as shown on the right hand side of the figure, or partly with the tubes, *b*, and partly with the tubes, *d*, as shown on the left hand side.

The tubes, *f*, are not only intermeshed with the tubes, *b* and *d*, but are arranged in close proximity thereto, an arrangement rendered possible by their disposition in single rows, and in this way the mutual heat radiation between the tubes prevents the superheating tubes, *f*, from attaining an excessive temperature when the flow of steam through them is diminished or entirely discontinued. Under normal conditions of working this mutual radiation in no way diminishes the efficiency of any of the tubes, *b*, *d* or *f*, but on the reduction of power or shutting down of the plant which is supplied with steam by the boiler, the radiation between the superheating tubes, *f*, and the water-containing tubes, *b* and *d*, will be paramount in determining the temperature of the superheating tubes.

It will be observed that an escape space is provided about midway the height of the boiler between upper and lower groups of superheater tubes. This space lies outside of the bank of closely spaced water tubes and gases after impinging against these water tubes and giving up heat thereto will escape through this space. Escape spaces are also provided between the superheater tubes and the water drums, these spaces will modify the lateral passage of the gases and their action on the superheater tubes to secure the proper heating effect.

Having now particularly described and ascertained the nature of our said invention and in what manner the same is to be performed, we declare that what we claim is:

1. In a water tube boiler of A form having a steam drum, and two water drums all arranged triangularly with their axes substantially horizontal and rows of upwardly convergent straight water tubes extending between the water drums and the steam drum, and with the fire space between the convergent water tubes, which are closely spaced apart adjacent the fire space, the

combination therewith of a plurality of rows of superheater tubes in single layers intermeshed with single layers of water tubes out beyond the closely spaced water tubes, the superheater tubes of each row being axially parallel with the axes of the drums and spaced apart for the passage of the hot gases laterally between them at different heights as received between the water tubes at different levels, and located in close proximity to the water tubes for the transfer of heat to the latter, said superheater tubes being arranged in groups with spaces between the groups for the escape of the hot gases laterally of the tubes, said lateral escape spaces lying toward the outside of and at a point intermediate the length of the bank of closely spaced water tubes and parallel with the axes of the drums, substantially as described.

2. In combination in a water tube boiler, a steam drum, two water drums all arranged triangularly and with their axes substantially horizontal, rows of straight water-heating tubes disposed with their axes substantially at right angles to the axes of said drums and connecting said water drums to said steam drum, a plurality of rows of superheating tubes disposed with their axes substantially parallel to the axes of said drums and lying transversely of said water tubes in single rows between single rows of said rows of water tubes, and in sufficiently close proximity thereto for transfer of heat from the superheater tubes to the water tubes, chambers within said water drums to which the feed water is directly fed, straight feed water heating tubes disposed with their axes substantially parallel to the axes of said water tubes connecting said chambers with said steam drum, and further superheating tubes disposed in single layers between said straight feed heating tubes and said water tubes and with their axes substantially at right angles to said feed heating and said water tubes, and in sufficiently close proximity thereto for transfer of heat from the superheater tubes to the water tubes.

3. In combination in a water tube boiler, a steam drum, two water drums all arranged triangularly and with their axes substantially horizontal, rows of straight water-

heating tubes disposed with their axes substantially at right angles to the axes of said drums and connecting said water drums to said steam drum, a plurality of rows of superheating tubes disposed with their axes substantially parallel to the axes of said drums and lying transversely of said water tubes in single rows between single rows of said rows of water tubes, and in sufficiently close proximity thereto for transfer of heat from the superheater tubes to the water tubes, chambers within said water drums to which the feed water is directly fed, straight feed water heating tubes disposed with their axes substantially parallel to the axes of said water tubes connecting said chambers with said steam drum, and further superheating tubes disposed in single layers between said straight feed heating tubes and said water tubes and with their axes substantially at right angles to said feed heating and said water tubes, and in sufficiently close proximity thereto for transfer of heat from the superheater tubes to the water tubes, the whole of said superheating tubes being arranged in groups with spaces between the groups for the escape of hot gases.

4. In combination in a water tube boiler an upper steam drum, two lower water drums, water tubes extending from the lower water drums to the upper drum, on each side of the fire space, the water tubes nearest the fire space being closely spaced and those more distant from the fire space being more widely spaced and two groups of superheater tubes arranged at each side of the boiler and toward the outer side of the water tubes and in single layers between single layers of widely separated water tubes, said groups of superheater tubes having escape spaces for the gases between them and having also escape spaces between said superheater tubes and the upper and lower drums, substantially as described.

In testimony whereof we affix our signatures in presence of two witnesses.

CHARLES ALGERNON PARSONS.
STANLEY SMITH COOK.
